UNITED STATES PATENT OFFICE

WILHELM ROHN, OF HANAU-ON-THE-MAIN, GERMANY

WATER-COOLED MOLD

Application filed October 7, 1930, Serial No. 487,084, and in Germany July 8, 1929.

This invention relates to water-cooled ingot-molds, more especially to water-cooled molds formed by an inner and an exterior tube between which ribs for guiding the cooling medium are provided.

The object of my invention is to provide molds of this kind in which a satisfactory transmission of heat from the inner tube to the cooling medium is warranted.

10 The invention is illustrated in the annexed drawings, of which

Figure 1 is an axial section of a cooling mold according to the invention.

15 Figure 2 is a cross section and shows a modification of the cooling ribs.

Figure 3 is a cross section similar to Figure 2 and shows a further modification of the cooling ribs.

20 Figure 4 shows a detail, namely a screw-shaped body for insertion in the cooling passages.

Figure 5 shows an arrangement for exchanging the inner tube.

25 Figure 6 is an axial section showing a modified form of a cooling mold according to the invention.

Figures 7a and 7b show different forms of construction of the band for forming the spiral path.

30 Figures 8 and 9 show forms of construction for stiffening the spiral path.

Figure 10 shows a method of packing the ends of the molds, and

35 Figure 11 illustrates a device for tightening and releasing the bottom plate.

Figure 12 shows a casting machine in which are assembled a number of ingot molds.

Referring first to Figure 1, the mold consists of a comparatively thin inner wall *a* which is adapted to define the cast molten metal. The ribs *b* which guide the cooling water, are not formed integral with the inner mold wall *a*, but on the contrary may

45 either be independent or connected to the outer casing *c*. The ribs *b*, which guide the cooling water, are sharpened on their side turned towards the actual mold wall *a* so as to form cutting edges whereby contact between *a* and *b* only takes place along a suit-

ably narrow line. In this manner there is obtained the result that the actual mold wall *a* does not have any points at which the passages of heat from *a* to the cooling water is liable to be defective. As shown in Figure 55 2 the cutting edge of the guide ribs *b* may be partly removed whereby the ratio between remaining portions of the cutting edges and the removed portions may be differently selected. In many cases the cutting edge of 60 the guide ribs *b* may preferably have an appearance similar to saw teeth. With such an arrangement the inner mold wall *a* is held and supported effectively at the points *d*, *d*, while between these points narrow slits 65 *e*, *e* are provided between the mold wall *a* and the ribs *b* through which a small quantity of water can pass from the cooling passage I directly into the cooling passage II parallel to the main axis of the mold. In 70 the accompanying drawings the width of these slits is magnified to be some what clearer. By suitably selecting the separate dimension it is possible for all the points of the inner mold wall *a* to be in contact with 75 water in a substantially uniform manner, and that no points are present where there is a lower removal of heat. A very efficient utilization of the whole cooling capacity of the water which flows thru can, in this case, 80 be obtained in that propeller-like guide bodies *f* (Figure 4) are inserted in the separate cooling passages so that a whirling movement is superposed on the flow of water in the main direction of flow. 85

When constructing the molds in the described manner the outer casing *c* and the cooling ribs *b* need only be produced once, while the inner mold, which is very inexpensive by reason of its shape, can be exchanged 90 in a short time. This exchange can, for example, be effected in the manner illustrated in Figure 5 in which *g* indicates a flange provided on the outer casing *c* and *a* is again the inner mold wall. Into a recess between 95 both parts there is fitted and endless rubber ring *h*, for example of circular cross section, which is so compressed by the pressure of the flange *i*, acting as a stuffing box, that a water and pressure tight closure is obtained 100

between the inner mold wall *a* and the outer casing *c*. For a round mold for a capacity of for example 100 kg., effective length 850 mm. and an internal diameter of 140 mm. 5 there is used as the inner member a seamless copper pipe of 5 mm. wall thickness and which only weighs about 20 kg. Its renewal does not require any greater expense than the difference in price between new copper 10 and old copper. In such molds steel blocks have been formed at a casting temperature of 1650° C. in pieces amounting to more than 2,000 without the least damage to the inner copper pipe being noticeable, while the usual 15 molds made of hematite cast iron used for casting steel have on an average a life amounting to about 130 castings. Figures 1 and 5 show such molds, the outer jacket together with the water guiding ribs as a whole 20 being made by casting.

In some cases the manufacture of the molds may be simplified by forming both the jackets of the molds and the guiding ribs from rolled material, whereby the manufacturing costs 25 are considerably reduced and, on the other hand, it is rendered possible to exchange the guiding ribs if required. Moreover, another advantage is attained inasmuch as the jacket of the mold may be made from one single 30 piece closed in itself, whereas a mold as shown in Figure 1, for instance, is preferably made of two longitudinal halves which are connected by flanges.

A mold of this kind is illustrated by way 35 of example in Figures 6, 8, and 9 of the drawings. In this case as an outer casing a pipe *l* is used and the guide ribs for the cooling water are formed by a suitably shaped band *m* surrounding the inner pipe *k* of the mold. 40 An example of construction is illustrated in Figure 6, while Figures 7a and 7b show by way of example forms of construction of the strips *m'* and *m''* before being spirally wound around the pipe forming the actual mold. 45 The spiral path formed by the strips *m'* and *m''* may for example be simply fitted into the pipe forming the outer casing, and if necessary soldered to this at points or throughout the length thereof.

50 The spiral path may also be stiffened before inserting it into the outer pipe by rods *n* extending therethru as shown in Figure 8 or by means of longitudinal strips *o* as shown in Figure 9, whereby it is not necessary to secure them to the outer pipe or preferably only to secure them at a single point or some few spots. If the shape of the blocks to be formed is conical the inner mold pipe may, for example, be readily brought into the desired 55 shape, for example, by forcing over a conical mandrel.

In order to enable the outer casing to be formed from a cylindrical pipe the guide strip adapted to be wound spirally is in this 60 case preferably made conical, that is to say 65

is made wider at one end than at the other.

Figure 10 shows a particularly simple form of construction of the packings at the ends of the molds. In this case the jacket pipe is provided at both ends with an internal 70 thread or with a recessed extension so that the ring *p* serving as a counter bearing for the rubber ring *q*, forming the packing, can be screwed or fitted into position. The inserted outer ring which is screwed in position, or which is tightened by separate screws when an internal screw thread is not provided, compresses the rubber packing and thus forms a fluid-tight joint. 75

It is also possible to screw at one of the ends of the pipes provided with an external thread, a flange or plate *r* which may serve for the reception of crane eyes *s* or securing devices for the base plate. 80

If the mold is to be used for oscillating castings or centrifugal casting it is possible during the same operation as the cutting of the screw thread to turn the bearing surfaces for the bearings or roller bearings. These however may also be provided in the 85 flanges which are screwed in position.

It is preferable also to provide a device for tightening and releasing the base plate and for removing the blocks from the mold. This device may consist of a guide rod *t* (Figure 11) bent in two directions, which for example can be pressed into position and released by means of an eccentric *u* with or without an interposed spring, and at the same time is capable of being swung laterally 90 so as to conveniently release the base plate *v* and the ingot which has been cast. 100

The above explanations have been given in connection with a conical mold, but it will be understood that the same principles of 105 constructions can be applied with the same or greater advantage to molds of any other suitable shape e. g. for flat billets to be rolled into strips or sheets. If the heat conductivity of the metal to be cast or one of its properties renders it necessary an inner pipe of a metal other than copper may be used or substituted therefor. 110

This extremely simple and inexpensive yet very suitable type of mold is also adapted as 115 an element for casting machines in which a number of such molds are mounted together on a turn table or on another returning conveying appliance with or without an oscillating device for the separate molds as illustrated in a schematic manner by Figure 12. According to this figure the molds *A* constructed as described above are put upon a turn table rotatable in the direction of the arrow *w*. By means of shells *x* and rods *y* the single molds *A* are connected to a disk *z* capable of being oscillated, as indicated by 120 a two-pointed arrow. By means of such a device, which for example contains six or 125 eight separate molds, it is possible to cast 130

charges of many thousands of kilogrammes mechanically into small ingots by avoiding the tedious movement required for conveying and carrying the ladle with the liquid metal 5 into accurate relative position to every single mold. These small ingots can subsequently without any rough or preliminary rolling be treated directly in continuous rolling mills so as to shape the final product. The ingots 10 mechanically cast into a cooled mold show an excellent fine and uniform casting structure. If these cooled molds are oscillated during casting metals and alloys, which normally have a casting structure little suitable for 15 rolling, acquire such a satisfactory structure that the ingots can be directly subjected to a continuous rolling mill without liability to disturbance.

The inexpensive production and easy 20 capability of exchange of the actual mold forming the feature of the Figures 1—5 and the additional feature of constructing the outer casing substantially of a simple internally smooth pipe and the formation of the 25 partitions and ribs from spirally wound strips for guiding the water and which on the inner side are sharp edged or are provided with sharp edged projections, constitute the essential features of the present 30 invention.

I claim:—

1. A water-cooled ingot-mold having a thin wall of suitable metal adapted to surround the ingot to be cast, comprising a jacket and ribs for guiding the cooling water arranged in the space between the said wall and jacket and forming a helical path for the cooling medium, the said ribs being formed on the side turned towards the inner wall 40 as a cutting edge.

2. A water-cooled ingot-mold having a thin wall of suitable metal adapted to surround the ingot to be cast, comprising a jacket and ribs for guiding the cooling water arranged in the space between the said wall and jacket and forming a helical path for the cooling medium, the said ribs being formed on the side turned toward the inner wall as a cutting edge, and the latter being partly 45 cut away to form direct passages from one to the next winding.

In testimony whereof I affix my signature.
WILHELM RÖHN.
